UNITED STATES PATENT OFFICE

LAWRENCE M. PERSONS, OF CHICAGO, ILLINOIS, ASSIGNOR TO COOK ELECTRIC COMPANY, OF CHICAGO, ILLINOIS, A CORPORATION OF ILLINOIS

FUEL-FEED SYSTEM

Application filed May 31, 1924. Serial No. 717,134.

This invention relates to a fuel supply system having particular application to liquid fuel burners, and it has for its general aim the production of a novel method of and 5 means for feeding fuel to the burner, such that, notwithstanding the varied operating conditions accompanying the use of liquid fuel burners, the fuel supply shall be at all times ample to meet the requirements of the 10 burner.

Fuel feed systems now generally employed in fuel burning systems have proven to be deficient in one or more respects. These systems most commonly use a pump of the gear 15 type for drawing the fuel out of the bulk supply tank and feeding it to the burner. One of the objections to systems employing a gear pump is that air may leak into the system by way of the suction pipe between 20 the pump and the supply tank, and the pump is entirely incapable of indicating that the leakage is in the suction line.

It is obvious that the presence of this uncontrolled supply of air in the fuel will have 25 a detrimental effect on the operation of the burner. Furthermore, as a general rule, gear pumps are otherwise undesirable for use in fuel feed systems. They lack the ability to provide a uniform supply of fuel, and 30 do not permit of such accurate control in their operation as is required in fuel burning systems.

The primary object of my invention is to produce a fuel feed system which will eliminate 35 the deficiencies of prior systems, including those above referred to, and at the same time to provide a means of exceeding simplicity which is certain and efficient in operation, and devoid of delicate mechanism which 40 is apt to require constant attention and frequent repair.

In carrying out my invention, I employ 45 a means for pumping the fuel positively from the bulk supply tank into an elevated receptacle of small size and capacity; which means is adapted to operate intermittently under the control of the level of the fuel so as to maintain in the receptacle a volume of fuel 50 never exceeding a predetermined maximum

but always adequate to meet the needs of the burner.

For operating the pump I employ preferably a rotary electric motor adapted to effect the desired movement of the fluid and obtain 55 a positive pumping action which is constant and certain upon each stroke of the pump, and consequently may rely upon the flow of the fuel with more certainty than when some other form of prime mover is adopted. 60

A further object of the invention is to provide a fuel feeding system embodying a reserve supply tank associative with an elevated pump receptacle, both of which are provided with corresponding liquid levels, 65 preferably above the level in the bulk supply tank. This arrangement allows the liquid, seeking its own level, to flow into the reserve supply tank from the receptacle until the latter is filled, whereupon the pump will 70 cease operating unless the burner is in operation. It is obviously advantageous to retain the fuel in the reserve supply tank until the bulk supply is gone so as to serve as a 75 warning to the owner that a limited supply of fuel is on hand. The connection leading to the reserve supply may therefore be valved.

As a means of indicating a leak in the suction line, it is an object of this invention to utilize a visible strainer located adjacent the 80 pump. The strainer will also serve as an air receiver to absorb shocks in the line and will indicate by bubbles the air drawn into the suction line at points where leakage occurs.

In order to apprise those skilled in the art how to construct and practice my invention, I shall now describe an embodiment thereof in connection with the accompanying drawings.

In the drawings:

Figure 1 is a side elevational view in the form of a diagrammatic layout illustrating an embodiment of my invention in which a hand pump may be used in connection with 85 the power driven fuel feed pump;

Fig. 2 is a similar view with the hand operated pump omitted;

Fig. 3 is an enlarged side elevational view 90 of the fuel feed pump;

Fig. 4 is an enlarged sectional view taken on line 4—4 of Fig. 5;

Fig. 5 is a transverse vertical sectional view of the fuel feed pump, taken on line 5—5 of Fig. 4; and,

Fig. 6 is a transverse sectional view taken on line 6—6 of Fig. 5.

Referring to Fig. 2, the fuel feed system, in which I have chosen to illustrate an improved embodiment of my invention, comprises a bulk supply tank 10, constituting a source of fuel supply for a burner 11. The latter may be equipped with a mixing chamber (not shown), to which the fuel is pumped by a fuel feed pump 12.

The pump 12 is in communication with the bulk supply tank 10 by means of a suction pipe 13. The fuel leaves the pump 12 by way of a pipe 14, which is in communication with burner 11. As long as a supply of fuel is in the bulk supply tank 10, the pump 12 functions to draw out the fuel and allow it to flow to the burner 11.

As a means of warning to the owner of the building that the fuel in the bulk supply tank 10 is exhausted (and for other advantageous reasons), I provide a reserve supply tank 15. A pipe 16 extends from the pipe 14 to the lower end of the reserve supply tank 15. In pipe 16, a valve 17 is furnished to normally cut out tank 15.

When the bulk supply tank 10 is emptied, the valve 17 may be opened and the fuel in tank 15 consumed. Usually this furnishes ample time to the owner of the building in which to refill the bulk supply tank 10.

As a means of safety it is customary to allow but a small quantity of fuel in the house at any one time. Hence, it is preferable to place the bulk supply tank outside of the building, and in most instances to bury it in the ground. As is illustrated in the drawings, fuel is drawn into pump 12 and retained in a receptacle 20 forming the lower body portion thereof. From receptacle 20 fuel is allowed to flow, say by gravity, through the connection 14 to the burner 11. Fuel pump 12 may be attached at any convenient point within the building. I have found, however, that it is desirable to locate it so that the fuel level in the receptacle will correspond with the fuel level in the reserve supply tank 15.

Pump 12 functions to operate automatically in supplying sufficient fuel to the burner 11. This automatic operation is under control of the level of the liquid. Consequently, when the level in the supply tank 15 lowers, the level in the receptacle 20 also lowers, which sets the pump into operation to draw fuel from the bulk supply tank 10. Hence, the pump 12 will refill the reserve supply tank 15 from the bulk supply tank 10 as soon as the latter is filled.

As before pointed out, the valve 17 may be normally kept closed so as to serve as a warn-

ing to the owner when it is necessary for him to open it for drawing fuel from the bulk supply tank 15, thus giving him an opportunity to replenish the supply in tank 10.

In Fig. 1, the system is illustrated with the hand pump 23 between the bulk supply 10 and the reserve supply tank 15. In this embodiment, a pipe 22 of slightly larger diameter serves as a connection between the tank 10 and the upper part of tank 15. Hand pump 23 may be suitably disposed upon a pedestal 24 located within the building and adjacent to the tank 15.

A suction pipe 24 is in communication with the pipe 22 on the intake side of the hand pump 23, and therefore, a part of the pipe 22 constitutes, together with the pipe 24, the suction line between the fuel pump 12 and the bulk supply tank 10. A valve 25 is provided to prevent the pump from drawing air into the suction line through the hand pump 23. Connection 14 communicates with the burner 11 and the reserve supply tank 15 in a similar manner. In connection with the disclosures of Figs. 1 and 2, an overflow pipe 26 extends from the bulk supply tank 10 and communicates with the upper portion of the receptacle 20.

Referring now to Figs. 4 and 5, the receptacle 20 is provided with an opening at its upper end. At this end, the wall is formed into a peripheral flange 27 for receiving a centrally apertured plate 28. This plate 28 serves as a gasket between the flange 27 and the motor housing 30. Within the upper end of receptacle 20, a pump cylinder 31 is disposed, and in this cylinder a flexible diaphragm piston 32 is adapted to be mounted. Diaphragm piston 32 is preferably in the form of a bellows with its lower end closed by means of a plate 33 and its upper end rigidly fixed to plate 28 by means of a soldered joint or some other suitable fastening. Cylinder 31 is of slightly larger diameter than piston 32, so that the fluid is adapted to be drawn into the chamber of cylinder 31 upon the up-stroke of the piston.

Liquid fuel enters the pump by way of the suction pipe 13 or 24 which are in communication with a port 35. Associated with the piston chamber and receptacle 20 is an auxiliary chamber 36 constituting in reality a visible strainer 37, but having in addition the dual function of indicating any leakage in the suction pipes 13 or 24, and of serving as an air receiver to absorb shocks in the line. Fluid entering the chamber 36 will rise a certain distance, passing through a screen 38 and into a passage 39 by way of a port 40. By referring to Fig. 4, it will be noted that passage 39 communicates with a valve chamber 41, the in-take of which is provided with a check valve 42 which permits a one way flow of the liquid fuel. The outlet of the valve chamber 41 is in communication with

the piston chamber 31. The fluid, when flowing into the chamber, will be expelled by the expansion of piston 32 through the port 43 and into the receptacle 20 by way of a port 44.

5 The drive for the piston 32 comprises generally a rotary electric motor 45. As before mentioned, the motor housing 30 serves as a closure for the open end of receptacle 20, thus 10 disposing the motor directly over the pump and constituting it an integral unitary part of the construction. The motor shaft 46 may extend downwardly toward piston 32 for completing a direct drive with the latter. Housing 30 is enlarged at 47 to accommodate a bearing sleeve 48, into the lower end of which a threaded plug 49 is adapted to be fitted. A thrust bearing 50 rests upon the upper end of plug 49 to provide a suitable end bearing 15 for the motor shaft 46. The direct drive between the motor and the piston 32 is accomplished by the provision of a worm 51 on the motor shaft 46, which worm meshes with a worm gear 52 suitably carried by a 20 transversely disposed pintle member 53. This pintle member 53 may be suitably journaled in the housing 30, say at the points designated 54 and 55.

25 A rigid connection with the piston 32 is provided through a piston rod 56 which is pivoted to the pintle 53. This rigid connection causes the piston to assume a slight transverse movement as well as a longitudinal movement when actuated.

30 Liquid fuel entering the receptacle 20 will rise to a predetermined level. This level is controlled by a float 60 operating a submerged snap-over switch 61 suitably arranged in the motor circuit. I provide float 60 and snap-over switch 61 in the form of a detachable unit. This unit is adapted to be mounted, in electrically insulated relation, on the under side of pump cylinder 31 by means of a fastening 62. A vertically depending support 45 64, provided at its upper end with a pair of lateral extensions 65, and at its lower end with a similar pair of lateral extensions 66, is adapted to carry float 60 in a manner permitting vertical movement thereof. A 50 pair of apertured lugs 67 are secured to the upper end of the float 60. A yoke 68 is adapted to furnish a loose pivotal connection between the extensions 65 and the lugs 67, so that the resultant upward pressure of the 55 fluid will permit the float to move vertically or parallel to the support 64.

A similar connection is provided at the lower end of float 60, this connection comprising apertured lugs 69, receiving one side of a yoke 70. A second yoke 71 is arranged to cooperate with the yoke 70 and receive one end of the coil spring 72. The opposite end of the spring 72 is fastened to yoke 70. A contact lug 73 is carried by a terminal 74 60 to which one of the lead-wires of the motor

circuit is connected. The opposite lead-wire is grounded to frame 64 at a point designated 75.

Float 60 will tend to maintain its position, either on the rise or fall of the fuel level in 70 receptacle 20. Assuming that the float is in its lower position, as illustrated in Fig. 5, spring 72 tends to draw the opposite ends of yoke members 70 and 71 together, but this movement is restricted by the lower side of float 60 engaging the upper edges of lugs 66, and the yoke 71 engaging terminal lug 73. The resultant upward pressure of the fuel against the float is counteracted by the spring exerting a downward force until it is sufficient to overcome the force of the spring. At the moment this occurs, the fuel level has approximately reached a level denoted by line A—B in Fig. 5. When yokes 70 and 71 are biased beyond dead center relation in an 80 upward direction, the spring 72 acts in a reversed direction and accelerates the upward movement of the float. Float 60 does not follow the fuel in its movement, but instead responds only when the fuel reaches level A—B 85 or level C—D. Thus the snap-over switch is actuated suddenly with a quick make and break movement to open and close the motor circuit. With this arrangement the motor 90 may be quickly started to actuate the pump 95 for pumping liquid into the receptacle 20 from the bulk supply tank.

Overflow pipe 26 is provided to return to the bulk supply tank the fuel should it rise above the predetermined level and flood the 100 receptacle 20. If for any reason the switch should fail, or a short circuit occur, which would permit the pump to continue operating, it is apparent that the overflow pipe will receive the excess fuel until the trouble is 105 remedied.

A lamp 80 may be inserted in the motor circuit for preventing damage to the motor windings by an overload in the circuit. This lamp is in series with the motor and will 110 function to consume excess current until the abnormal condition is removed. It serves, however, to inform one of this overloaded condition by lighting at this time.

I wish to emphasize the novel arrangement of the various parts of the system disclosed herein. With the fuel pump between the bulk supply tank, the reserve supply tank and the burner, the fuel may first be taken from the bulk supply tank and then from the reserve supply tank, but before the latter tank may be cut in, it is necessary to open valve 17 which serves to warn the owner that the bulk supply tank is empty. Furthermore, at this stage in the operation, the pump 120 will no longer operate, but may be operated again when the bulk supply tank is filled.

I claim:

1. A pumping unit comprising the combination with a motor having its housing pro- 125

- vided with means for attaching the motor to a support, of a motor driven pump and tank suspended from the motor, said tank receiving the liquid discharged by said pump.
2. A fuel feeding device comprising a chamber provided with a movable part for drawing fuel therein, an open end receptacle in communication with the chamber, a motor for driving said part, the housing of the motor serving as a closure for the open end of the receptacle, said housing provided with an auxiliary chamber therein for communication with the first chamber.
3. A pumping unit comprising the combination with a motor including a rotor and a shaft therefor, and including a housing having a base supporting said rotor on one side thereof, of a pump driven by said motor and carried by said motor base on one side thereof opposite the rotor, and a tank attached to said motor base, said motor base constituting a cover for the tank.
4. A pumping unit comprising the combination with a motor including a rotor, and a shaft therefor, and including a housing having a base supporting said rotor on one side thereof, of a pump carried by said motor base on one side thereof opposite the rotor, and a driving connection between said motor and said pump, the housing of said motor adapted to contain a body of lubricant to lubricate the motor, said driving connection being submerged in said body of lubricant.
5. A pumping unit comprising the combination with a motor including a rotor and a shaft therefor adapted to be operated with the shaft vertical, and including a frame member provided with a bearing supporting said rotor and having an opening therein adjacent to said bearing, of an extensible and collapsible pumping element and a cylinder associated therewith carried by said frame member on the side thereof opposite the rotor, a driving connection extending into said extensible and collapsible element from a point on said shaft, the opening in said frame member permitting communication between the interior of the frame member and said extensible and collapsible element for a common body of lubricant, said driving connection operating in said body of lubricant.
6. A pumping unit comprising the combination with a motor including motor housing and a base, of an extensible and collapsible pumping element and a cylinder therefor carried by said base on the side thereof opposite the motor, said base having an opening therein providing communication with the interior of said pumping element, and a driving connection between said motor and said pumping element, said motor housing and said pumping element containing a common body of lubricant, said driving connection being lubricated by said lubricant.
7. A pumping unit comprising in combination, a motor including a field shell, a pump driven by the motor, a fuel tank for receiving the fuel discharged by said pump, and a bracket provided on the field shell of the motor for mounting the pumping unit, said field shell serving as a cover for the fuel tank.
8. In a fluid supply system, a receptacle, pumping apparatus for supplying fluid to the receptacle, a rotary electric motor having a vertically arranged rotor for operating said pumping apparatus, said pumping apparatus comprising an expansible and contractible piston and a rod connected thereto and extending upwardly from the interior thereof, a pivotal connection for one end of the rod, a worm gear in operable driving relation with said pivotal connection, and a worm on the motor shaft meshing with the worm gear, said motor shaft arranged substantially parallel to the piston rod.
9. In a fluid supply system, a receptacle having an open end, pumping apparatus for supplying fluid to the receptacle, a rotary electric motor for operating said apparatus, said motor and said apparatus extending in substantially parallel planes, the housing of the motor cooperating with the open end of the receptacle and serving as a closure therefor, the shaft of the motor provided with a worm thereon, and a worm gear operably connected with said pumping apparatus meshing with the worm.
10. In a fluid supply system, a receptacle having an open end, pumping apparatus for supplying fluid to the receptacle, a rotary electric motor for operating said pumping apparatus, the housing of said electric motor arranged coextensive with the receptacle and serving as a closure for its open end, a driving rod extending from said pumping apparatus arranged substantially parallel to the motor shaft, and a positive driving connection between the driving rod and the motor shaft.
11. In a fluid supply system, a receptacle having an open end, pumping apparatus for supplying fluid to the receptacle, a rotary electric motor for operating said pumping apparatus, the housing of said electric motor arranged coextensive with the receptacle and serving as a closure for its open end, a driving rod extending from said pumping apparatus arranged substantially parallel to the motor shaft, and a positive driving connection between the driving rod and the motor shaft, said driving connection comprising a worm gear on the rod and a cooperating worm on the motor shaft.
12. A fuel feed pump adapted to supply fuel to a burner or the like by gravity feed comprising a receptacle and a pump cylinder

disposed within said receptacle, a pump in said cylinder, a motor for operating said pump, and a member for carrying said cylinder and said pump as a removable unit between said receptacle and said motor.

5 13. A fuel feed pump adapted to supply fuel to a burner or the like by gravity feed comprising a receptacle and a pump cylinder disposed at the upper open end of said receptacle, a piston operating in said cylinder for drawing fuel into said cylinder and for pumping the fuel into said receptacle, a motor for driving said piston, the housing of said motor being so formed as to serve as a cover for the open end of said receptacle, and an apertured plate to which said pump cylinder and said piston are secured as a removable unit from the upper end of said receptacle, said apertured plate being interposed between 15 said receptacle and said motor housing.

14. A fuel feed pump adapted to supply fuel to a burner or the like by gravity feed comprising a receptacle and a pump cylinder disposed at the upper open end of said receptacle, a piston operating in said cylinder for drawing fuel into said cylinder and for pumping the fuel into said receptacle, a motor for driving said piston, the housing of said motor being so formed as to serve as a cover for the open end of said receptacle, an apertured plate to which said pump cylinder and said piston are secured as a removable unit from the upper end of said receptacle, said apertured plate serving as a gasket between said receptacle and said motor housing, and a driving connection extending between said piston and said motor through the aperture of said plate.

15. A fuel feed pump adapted to supply fuel to a burner or the like by gravity feed comprising a receptacle and a pump cylinder disposed at the upper open end of said receptacle, a bellows piston operating in said cylinder for drawing fuel into said cylinder and for pumping the fuel into said receptacle, a motor for driving said bellows piston, the housing of said motor being so formed as to serve as a cover for the open end of said receptacle, an apertured plate to which said pump cylinder and said bellows piston are secured as a removable unit from the upper end of said receptacle, said apertured plate serving as a gasket between said receptacle and said motor housing, and a driving connection extending between said bellows piston and said motor through the aperture of said plate, the interior of said bellows piston being in communication with said motor housing to permit a lubricant to be retained therein for 55 lubricating the interior of said bellows and said driving connection.

16. Pumping apparatus comprising a pump chamber and a piston for drawing liquid into said pump chamber from a source 60 of liquid supply, a second chamber on the in-

take side of said pump chamber and into which the liquid is drawn before passing into said pump chamber, a connection between the source of supply and said second chamber, said connection being at a point below 70 the level at which said liquid rises in said second chamber, and means for indicating a leak in said connection, said means rendering visible air bubbles in the liquid as the liquid is drawn into said second chamber and ascends upwardly therein.

17. Pumping apparatus comprising a pump chamber and a piston for drawing liquid into said pump chamber, a second chamber on the intake side of said pump chamber and into which the liquid is drawn before passing into said pump chamber, a connection for discharging liquid into and below the level of the liquid in said second chamber, and means to indicate a leak in said connection, said means exhibiting air bubbles 80 rising in the liquid.

18. Pumping apparatus comprising a pump chamber and a piston for drawing liquid into said pump chamber, a second chamber having an inlet and an outlet, said outlet communicating with the intake side of said pump chamber, both said inlet and said outlet being below the level at which the liquid rises in said second chamber before 90 passing into said pump chamber, and means exhibiting air bubbles rising in the liquid as it flows through said second chamber for determining leakage of the liquid before it reaches said second chamber.

19. A pumping unit comprising the combination with a tank having one end open, a removable cover for said tank at said open end, a pump carried by said cover at its under side and within said tank for supplying liquid to said tank, and a motor for said pump upon said cover including a rotor and shaft therefor adapted to be operated with the shaft vertical and having provisions for extending through said cover and into said tank to drive said pump.

20. A pumping unit comprising the combination with a vertically arranged tank having one end open, a cover for said tank at said open end, a pump carried by said cover for supplying liquid to said tank, and a motor mounted exteriorly upon said cover and having its axis substantially vertical to provide a substantially vertical drive extending through said cover and into said tank for 110 driving said pump.

21. A pumping unit for a fuel feed system comprising, in combination, a tank having an open end and a cover therefor, pumping apparatus for supplying liquid to said tank, a rotary electric motor for operating said pumping apparatus, said cover and said pumping apparatus being arranged as a removable sub-assembly between said tank and said motor, said motor being mounted upon 125 130

said cover, and a drive arranged substantially vertically and extending from said motor through said cover and into said tank to drive said pumping apparatus.

5 22. A pumping unit comprising the combination with a receptacle having an open end, pumping apparatus for supplying liquid to said receptacle, a plate having an aperture therein serving as a closure for said open end
10 of said receptacle, and to which plate said pumping apparatus is carried on one side, a motor mounted upon said plate on the opposite side, and a rotary drive extending through said aperture in said plate and into
15 said receptacle to drive said pumping apparatus.

23. A pumping unit comprising the combination with a receptacle having an open end, pumping apparatus for supplying liquid to said receptacle, a plate having an aperture therein serving as a closure for said open end of said receptacle, and to which plate said pumping apparatus is attached on one side, a rotary electric motor mounted upon
25 said plate on the opposite side, said motor including a rotor and a shaft therefor adapted to be operated with the shaft vertical so that the housing of said motor serves as a closure for said aperture in said plate, and a drive extending from said motor shaft and passing through said aperture to said pumping apparatus.

24. A pumping unit comprising the combination with a motor including a rotor, and
35 a shaft therefor adapted to be operated with the shaft vertical, and including a housing having a base supporting said rotor, a pump driven from said shaft, a plate to which said pump is attached and upon which said motor
40 is mounted, and a tank into which liquid is pumped having an open end with said plate positioned over said open end as a cover therefor.

In witness whereof, I have hereunto subscribed my name.

LAWRENCE M. PERSONS.
